UNITED STATES PATENT OFFICE.

SIMON W. WARDWELL, OF PROVIDENCE, RHODE ISLAND, ASSIGNOR TO
UNIVERSAL WINDING COMPANY, OF PORTLAND, MAINE, A CORPORA-
TION OF MAINE.

WINDING-MACHINE.

SPECIFICATION forming part of Letters Patent No. 792,565, dated June 13, 1905.

Application filed June 4, 1904. Serial No. 211,204.

To all whom it may concern:

Be it known that I, SIMON W. WARDWELL, a citizen of the United States, residing at Providence, in the county of Providence and State 5 of Rhode Island, have invented new and useful Improvements in Winding-Machines, of which the following is a specification.

My invention relates to winding-machines, and particularly to that class of machines in 10 which the thread-guide bears at all times during the winding on the surface of the cop, receding from the winding-spindle as the yarn is built up thereon.

The object of my invention is to provide improved devices for preventing the guide from 15 returning toward the winding-spindle after it has been forced out by the growing cop.

The invention is fully set forth in the following specification, illustrated by the accompanying drawings, in which—

Figure 1 is a front view of the winding-machine; Fig. 2, a detail of the traverse-frame detent, being a sectional view on the line 1 1, Fig. 1; Fig. 3, a detail of the detent finger-lever, showing its relation to the traverse-frame.

The machine in general is of a familiar type known to those versed in the art as the "Universal Winding-Machine." It comprises, essentially, the main frame A, supporting bearings for the winding-spindle B and cam-shaft C, the latter carrying the cam (not shown) which reciprocates the thread-guide D. The thread-guide slides in the traverse-frame E, 35 which is pivoted on the cam-shaft C and adapted to swing to carry the guide away from the spindle. The traverse-frame carries a weight E' below its pivot-point which serves as a counterbalance for the frame and the mechanism it carries. In order that the cop may be wound hard and firm, it is necessary that the guide bear at all times upon the surface of the cop, and to provide for this pressure is applied to the traverse-frame to resist its movement outward from the winding-spindle. For this purpose I prefer to make use of the devices shown at G and described in my pending application, Serial No. 135,768, filed December 18, 1902,

in which the weighted arm a is connected to the lower arm of the traverse-frame and tends 50 to swing the latter to carry the guide toward the winding-spindle.

The cop-tubes employed for winding-machines are generally formed of paper or straw board made inexpensively and apt to have 55 rough irregular surfaces. If the thread-guide were allowed to follow in and out over this wavy surface in traversing the tube, the cop would be started with an irregular foundation and the irregularities would be magnified as 60 more layers were added. Also in the style of winding effected by this variety of machine the coils of thread cross and recross each other, and at each crossing one coil is raised above the other, so that the guide is pressed out- 65 ward beyond the plane of the original coils in any one layer. The in-and-out movement of the guide from this cause, if allowed, would also tend to accentuate the irregularities of the cop-surface; but it has been determined in 70 practice that if the guide is prevented from returning toward the spindle after being once forced outward the surface of the cop is maintained straight and regular during the winding. Various devices have been heretofore 75 designed to adapt the guide to reciprocate always in a straight path parallel to the surface of the winding-spindle; but my improved means accomplishes the desired result with a simple and positive mechanism. 80

The operation of the machine is controlled through a starting-lever J, which when shifted to start the winding is held in position by the detent H. This latter is formed as a sector, pivoted at h and supported concentric 85 with the axis of the traverse-frame E by the extension h', bearing on the arm l of the lever J. On the under side of the sector H is a V-shaped groove g, extending throughout its entire length. (See Fig. 2.) Extending parallel to the back of the traverse-frame and supported in bearings in the lug f² and leg e² of the frame is a rod e³, formed with a detent-arm e, bent at right angles thereto and having an extension e', tapered to correspond to the 90 groove g. At the outer end of the rod is fas- 95

tened a finger-lever f , bearing against the lug f^2 and serving to retain the rod in its bearings. The lever f is preferably made of sheet metal, with a portion formed to surround the 5 rod e^3 and adapted to bind upon the latter when clamped with the screw f^3 . Adjacent the top of the lever is fastened a double wire spring s by means of a rivet s^2 . With the lever properly adjusted the spring s engages a 10 portion of the frame E , tending to carry the lever outward and forcing the extension e' of the detent firmly into the groove g . Any tendency of the frame to move backward toward the winding-spindle is resisted by the 15 wedging of the detent in the groove; but the outward movement of the frame tends to swing the detent, and thereby releases its hold on the sector. It will be seen that the frame swings readily outward under the pressure of 20 the growing cop on the guide, and its movement is only resisted by whatever pressure is applied through the devices at G . The inward movement of the frame, however, is prevented by the detent e unless the latter is 25 released by the operator.

In removing knots, &c., and in piecing the 30 yarn the operator frequently moves the traverse-frame outward as far as possible to make room for his hand between the guide and the package. When it is desired to resume the winding, the guide is readily returned to the winding-spindle by pressing upon the lever f to release the detent from the sector. It is important, however, that the guide shall not 35 be pressed against the package with too much force or the latter might be injured by careless operators. To guard against this, I provide an arrangement whereby the movement of the frame is under perfect control of the 40 hand upon the operation of the finger-lever. To this end the back of the frame is formed with an extension e^4 , (see dotted lines, Fig. 3,) which besides serving for the spring s to bear on provides a convenient grasping place for 45 the operator's fingers. The most natural manner of operating the lever f will be with the thumb bearing against the portion e^4 and the forefinger pressing on the lever f . In this way a grasp of the traverse-frame itself is insured, and it is then under easy control of the 50 hand and may be moved at will to adjust the guide delicately against the package.

It will be seen that the devices above described are an improvement over any now in 55 use, having the advantage of extreme simplicity, positive action, convenience of operation, and least liability of being impaired through wear.

What I claim as my invention, and wish to 60 secure by Letters Patent, is—

1. The combination in a winding-machine with a winding-spindle, a traversing thread-guide and a frame to support the guide to move away from the spindle, of a member extending in the path of the frame and having a ta-

per groove, and a detent on the frame engaging said groove to resist the movement of the frame toward the spindle.

2. The combination in a winding-machine with a winding-spindle, a reciprocating thread-guide and a traverse - frame supporting the guide to move away from the spindle, of a member extending throughout the path of the frame and having a groove, and a detent hinged on the frame and adapted to be swung to engage 75 said groove.

3. The combination in a winding-machine with a winding-spindle, a reciprocating thread-guide and a frame supporting the guide to move outward from the spindle, of a member 80 extending in the path of the frame and having a tapered groove, a detent on the frame having a tapered extension and means to move the detent to engage the groove.

4. The combination in a winding-machine 85 with a winding - spindle and reciprocating thread-guide, arranged to recede one from the other, of a member in the path of travel and having a taper groove and a detent engaging said groove to resist the drawing together of 90 the spindle and thread-guide.

5. The combination in a winding-machine with a winding-spindle and a reciprocating thread-guide adapted to recede from the spindle with the increase of the cop, of a member 95 in the path of the guide, having a taper groove, and a detent connected with the guide and engaging the groove to resist the movement of the guide inward toward the spindle.

6. The combination in a winding-machine 100 with a winding-spindle, a reciprocating thread-guide, a swinging frame supporting the guide, and means to resist the movement of the guide away from the spindle, of a member in the path of the frame and having a taper groove, 105 and a detent on the frame arranged to engage the groove to normally prevent the movement of the guide toward the spindle, but releasable to allow said movement.

7. The combination in a winding-machine 110 with a winding-spindle, a reciprocating thread-guide and a traverse - frame supporting the guide to move away from the spindle, of a member extending in the path of the traverse-frame and formed with a taper groove, a detent pivoted on the traverse-frame to engage 115 said groove, a finger-lever for operating the detent and a spring engaging the frame and the lever to keep the detent normally engaged with the groove.

8. The combination in a winding-machine with a winding-spindle, a reciprocating thread-guide, and a swinging frame supporting the guide, of a sector supported concentric with the axis of the frame and having a taper 125 groove extending its length, a detent on the frame to engage the groove, a finger-lever adjustably connected with the detent and a spring engaging the lever and the frame to normally maintain the detent engaged with the groove. 130

9. The combination in a winding-machine with a main frame A, winding-spindle B, thread-guide D, and traverse-frame E pivoted on the frame A, of a sector H supported on the frame A concentric with the axis of the frame E and having a taper groove g , a rod e^3 extending through bearings in the frame E with an arm e at right angles to the bearing portion and formed with a wedge-shaped extension e' engaging the groove g , a finger-lever f formed with a portion surrounding the rod e^3 , a screw binding the lever on the rod, and a spring fastened to said lever and bearing on the frame E.
10. The combination in a winding-machine with a winding-spindle, a reciprocating thread-

guide and a traverse-frame supporting the guide to swing away from the spindle, and formed with an extension to be grasped by the operator's fingers, of a detent to normally prevent the movement of the guide toward the spindle, and a finger-lever for releasing the detent arranged to be operated by the grasping of the traverse-frame extension.

In testimony whereof I have signed my name to this specification in the presence of two subscribing witnesses.
